UNITED STATES PATENT OFFICE.

ADELMER M. BATES, OF CHICAGO, ILLINOIS, ASSIGNOR TO BATES VALVE BAG COMPANY, OF CHICAGO, ILLINOIS, A CORPORATION OF WEST VIRGINIA.

MACHINE FOR PRINTING BAG BLANKS.

Application filed March 22, 1920. Serial No. 367,687.

To all whom it may concern:

Be it known that I, ADELMER M. BATES, a citizen of the United States, residing at Chicago, in the county of Cook and State of Illinois, have invented a certain new and useful Improvement in Machines for Printing Bag Blanks, of which the following is a specification.

My invention relates to improvements in machines for printing bag blanks and has for one object to provide a new and improved means whereby the cloth or fabric which is afterwards to be made into a bag, may have printing applied thereto. The essential feature of the invention lies in the means provided whereby the spaces between the separate impressions on the blank may be varied at the will of the operator for the purpose of providing printed bag blanks of different lengths as is so often necessary when materials of different size, bulk, or character are to be packed or when it is desired to print bags of different capacity. In other words, my invention provides means for enabling the operator to space the separate impressions along the roll of cloth or paper which forms the bag blank. My invention is illustrated more or less diagrammatically in the accompanying drawings 30 wherein:

Fig. 1 is a side elevation of the machine with drive pulley broken away;

Fig. 2 is a section along the line 2—2 of Fig. 1;

Fig. 3 is a vertical section showing part of the platen or impression cylinder and a portion of two of the printing or plate cylinders;

Fig. 4 is a detail section along the line 4—4 of Fig. 1;

Fig. 5 is a plan view of a portion of the rewind mechanism with parts broken away;

Fig. 6 is a section along the line 6—6 of Figure 1 with parts in elevation;

Figure 7 is a section similar to Figure 3 showing a modified form;

Figure 8 is a section along the line 8—8 of Figure 7;

Figure 9 is a plan view of one end of the impression cylinder showing details of the cloth take-up.

Like parts are indicated by like characters throughout the drawings.

A is a main base frame being made up of a lower portion with integral brackets pro-

jecting upwardly therefrom and horizontal tie members tying them together. A¹ is a continuous feeding or driving chain made up of links adapted to ride on the sprockets A², A³, and A⁴. These sprockets are arranged in pairs on suitable shafts as shown so that there are two continuous parallel chains one at each side of the machine. The sprockets A⁴ are mounted on a drum A⁵ on a shaft A⁶. To one of these sprockets is bolted the driving member A⁷ in mesh with a pinion A⁸ on the drive shaft A⁹. A¹⁰ is a driving pulley on that shaft by which power may be applied through a belt from any suitable source. 79

B is a supply roller upon which is mounted the supply of fabric or paper which is to be printed, this material being preferably such fabric or paper as may be made into bag forms or bag blanks. B¹ is a strip of material to be printed. It extends from the roller B around the drum A⁵ back beneath it to the roller B² about which the printed strip of material is wound. B³ is a drive roller engaging the periphery of the roll 80 of cloth or fabric where it is wound onto the roller or spool B². These rollers B³ B² are mounted on a lever B⁴ pivoted for rotation about the shaft B⁵ and held by the counter weight B⁶ in such manner that the 85 rollers B³ B² are held snugly against the surface of the fabric on the spool B². B⁷ is a sprocket on the shaft A⁹. It drives the chain B⁸ which in turn drives a sprocket B⁹. This sprocket rotates the shaft B⁵ and that in turn causes the rotation of a pulley B¹⁰ on the shaft to drive through a belt B¹¹ which passes around an idling and tightening pulley B¹². The pulley B¹³ in turn drives the rollers B³ B² whereby the fabric 90 strip is frictionally driven by the rollers B³ from the drive shaft A⁹ and at a speed sufficient to take up the slack when the take up elements are at their greatest excursion. At other times, or between successive releasing steps of the takeup, the friction rollers can of course slip as they engage the fabric, thereby permitting continuous smooth operation. 100

C C are brackets in opposition to the drum A⁵. These brackets carry rotatably mounted thereon, the segmental printing rollers C¹ C². Each printing roller I have shown with three printing segments though there may be more or less. C¹ C², C³ C⁴, C⁵ C⁶, indi- 110

cate series of inking rollers associated in groups with each printing roller so that different colors may be printed, each printing roller printing one color of the series and each roller printing, in this case, three impressions on each revolution.

With the rollers shown cut away as they are and with the impression faces spaced on the rollers as they are there will be a series 10 of spaced impressions made on each bag blank, the distance between such impressions being fixed. In the past, it has been customary when desirable to change the distance between the impressions for varying sizes of 15 bags, to change the printing rollers themselves and this made it so difficult and complicated that frequently the wrong sizes were printed with accompanying serious waste of material to avoid expense and delay caused 20 by stoppage of the machine to change the rollers. My invention therefore provides means to make it possible without changing the rollers in any way, to take up a varying or controlled amount of slack in the fabric 25 between each impression so as without stopping the operation of the machine and without interfering with its continuity, to vary the distance between the impressions which subsequently are to be located one on each 30 bag blank.

The platen roller A³ is made with a series of transverse pockets D¹ in its periphery. In each of these pockets is mounted a cross bar D⁴ having a tapered working end projecting normally more or less beyond the periphery of the roller. Each of these cross bars has secured to its opposed ends, adjusting links D² D³ terminating at their inner ends in rollers D⁵ which ride in cam slots 35 D⁶ located in adjusting plates at either end of the drum A³. These adjusting plates are mounted for rotation on the faces of the drum. They are annular and are exteriorly toothed to mesh with pinions D⁷ on a key 40 shaft D⁸ squared at its ends whereby the operator may by use of a key or crank, rotate the adjusting plates to move the cross bars D⁴ outwardly beyond or retract them inwardly within the periphery of the drum A³. 45 D⁹ D¹⁰ are spaced rods extending across between opposed links of each chain and are braced and stiffened by the V-shaped beam members D¹¹ D¹² which by their truss formations prevent bending of the rods intermediate their ends. The relation between these 50 parts is such that the outward movement of the cross bars D⁴ brings successive bars between the rods D⁹ and as these successive bars penetrate between these rods they draw up a certain amount of the fabric and take 55 up the slack represented by the difference between the tangent X-X' and the two sides of the triangle X-Y-X' around the working edge of the cross piece. The further out 60 the cross piece projects, the more slack there

will be drawn up by the co-operation of the cross piece D¹ and the pins D¹³. It will be noted that each group of pins and cross pieces holds the cloth with the slack taken up, while the printing takes place and once 70 the slack has been taken up, these pins and cross pieces retain their cooperative relation and hold the slack until that part of the fabric or cloth which they engage has passed clear around the drum A³. The printing 75 rollers, themselves are cut away a little more deeply than would otherwise be the case as at D¹⁴ so that there can be no chance for any interference between the printing roller and the slack drawing cross pieces. 80

This slack may be drawn up by other means as indicated, for instance in Figures 7 and 9 inclusive. In this case, the drum E, has in its face, a series of axial slots E¹, outwardly flared as indicated. On the chain extending 85 between the links are curved channel like members E² adapted to penetrate within the slots E¹ and be thrust therein by spring arms E³ carried on the links. The inward movement of these cross channels is limited 90 by the adjusting push rods E⁴ terminating in rollers E⁵ engaging cam slots E⁶ in an adjusting plate E⁷ which may be rotated in any suitable manner to move the push rods E⁴ in or out to control the depth to 95 which the slack pulling channels E² may penetrate in the slots E¹ to pull the slack in the cloth.

It will be evident that while I have shown in my drawings an operative device, still 100 many changes might be made in size, shape, and arrangement of parts without departing materially from the spirit of my invention, and I wish therefore, that my drawings be regarded as, in a sense diagrammatic. 105

My device is primarily intended for use in taking up the slack of bag blanks which are to be printed but I want the term bag blanks and the use of terms and descriptive matter referring to the product and to printing understood broadly because I might print or impress or reproduce designs, lettering or the like on any kind of flexible continuous strip material. The designs might be reproduced by printing or embossing or cutting or perforating or by a photographic process and the designs printed on the blank might be for bag blanks or clothing or newspapers or magazines or anything where such a design could be used. The word slack is 110 used throughout the specification and claims to indicate the material mechanically taken up between each printing impression along the strip or between each section of cloth which is about to receive a printing impression. The amount of material which would normally be wound about the drum A³ is increased by the adjustable bars D⁴ which tend to stretch the cloth in a series of plane 115 surfaces. These planes are broken by the 120

125 130 135

confining members D^s which fit over the bars D^1 and pin the cloth to the surface of the drum at the sides of the bars D^1 . The excess material is thus concentrated adjacent to the points where the bars D^1 project and of course those are the points which fit in between the printing impressions. At each such point, not only is some of the additional material drawn about the drum, by the bars D^1 taken up, but a degree of slack is also taken up between the adjacent members D^s , the cloth on each of the unbroken drum platen sections being tightly drawn to receive the printing impression. The slack or folded or bent cloth between each printing impression or each as yet unprinted section of cloth may be adjusted by radial movement of the bars D^1 which thus adjusts the distance between the printing impressions on the finish cloth strip and in a positive sense spaces them along said strip in relation to each other.

The use and operation of my invention are as follows:

25 The operator first places in position on the frame a spool containing a roll of blank, that is, unprinted bag forming material, and screws up the hand screw to tighten the bearings sufficiently to hold the spool or spindle in place in the usual manner. He then draws the material out and holds the end of the strip against the face of the platen roller. He then rotates this roller by hand or otherwise, thus rotating the chain with it, 35 and continues this rotation until the end of the strip has passed clear around the printing roller, and can be carried over to the spindle which is to hold the roll of printed goods. He will then attach the end of the 40 strip to the spindle.

This may or may not be done with the slack pulling cross pieces or member projecting beyond the periphery of the platen roll. In any event, the operator will either before 45 or after the fabric is in place, rotate the adjusting or cam disc to cause the slack pulling members to project a suitable distance beyond the periphery of the platen roll, to take up the desired amount of slack between 50 impressions and preferably, there will be a scale of markings on the roller whereby he can set the apparatus for any desired spacing of impressions.

The apparatus is then started and the 55 chain will be driven to cause the bag forming material to be fed along around the face of the platen roller to receive its impressions, the material being drawn out by co-operation of the chain and slack pulling bars between the separate impressions.

The weight of the spindle carrying the unprinted material and the friction of its bearings will be sufficient to resist the drawing out of the cloth enough to keep it tight. 65 The cloth or fabric as it is drawn away

from the platen roller will be wound on the spindle and a proper rate of speed is provided by the fact that the power which rotates this printing spindle and roll of printed material is supplied to the periphery of the roll so that while the rotational speed of the spindle may vary as the roll changes in diameter, still the linear speed of the feed tending to draw the printed material away from the platen roller and wind it upon the storage roll will be substantially constant.

The friction roller which engages the printed fabric is held thereagainst by the counter weight on the end of the lever and since the drive from the main drive shaft is applied to a shaft at the fulcrum of the lever, change in the angular position thereof can not effect any change in operation, and the friction drive from the fulcrum shaft is so set that there is a tendency toward a more rapid speed than is permitted by the rotation of the chain, and the slight slippage thus resulting insures that the cloth or paper will always be wound on the roll and drawn off the platen roller as tightly and snugly as is possible.

The printing rollers in opposition to the platen roller are merely the ordinary type of printing roller rotated by the rotation of the platen roller and carrying a plurality of separate impression members so that if the roller makes a plurality of impressions on the bag strip, at each revolution, one or more of these rollers can be used at the same time. If only one color were being printed, perhaps only one would be used, or if more than one impression or mark were to be made on each bag, perhaps other of the rollers might be used. At any rate, the arrangement of these rollers gives to the operator a wide range of choice both in color scheme and arrangement.

The operation of the modified form and the preferred form so far as the adjustment of the slack pulling members is concerned, is the same practically except that in one case the rotation of the cam disc forces the slack bars out so that the cloth is drawn outwardly into the chain and in the other case, the operation of the cam draws the stops back towards the center of the roll and permits the spring supported bars on the chains to penetrate slots in the platen roll and draw the fabric inwardly toward the center. The preferred form will probably be a little simpler, lighter and less complicated, but in many conceivable conditions, the modified form would be better.

I claim:

1. The process of forming a series of separate spaced designs upon a continuous strip of flexible material and adjustably controlling the distance between such separate designs which consists in applying separate spaced designs on the strip and

in taking up a predetermined controlled amount of slack in the material between each pair of designs.

2. The process of printing a series of 5 separate spaced impressions on a continuous strip of flexible blank material and adjustably controlling the distance between such 10 separate impressions which consists in applying separate spaced designs on the strip and in taking up a predetermined controlled amount of slack in the material between each pair of impressions.

3. The process of forming a series of 15 separate spaced designs upon a continuous strip of flexible material and adjustably controlling the distance between such designs which consists in performing a plurality of separated design forming acts at 20 different points along the path of the material, and in taking up a predetermined controlled amount of slack in the material between each pair of designs, and holding such slack while all of such separate acts are being performed.

25 4. The process of printing a series of separate spaced impressions on a continuous strip of flexible blank material and adjustably controlling the distance between such 30 separate impressions which consists in giving to the material a plurality of separate impressions at different points along its path through the machine to form a series of built up designs, and in taking up a predetermined controlled amount of slack in 35 the material between each pair of impressions.

5. The process of printing a series of 40 separate built up designs upon a continuous strip of flexible blank material and adjustably controlling the distance between such 45 separate designs which consists in giving to the material a series of successive impressions at different points during its travel to build the design, and taking up a predetermined controlled amount of slack in the material between each pair of designs.

50 6. The process of printing a series of separate built up designs upon a continuous strip of flexible blank material and adjustably controlling the distance between such 55 separate designs which consists in giving to the material a series of successive impressions at different points during its travel to build the design, and taking up a predetermined controlled amount of slack in the material between each pair of designs, and holding the slack taken up and carrying that slack through the cycle of operations without releasing it until the slack has 60 passed clear through the printing press.

65 7. Machine for printing a series of separate spaced designs on a continuous length of flexible material comprising a platen and an impression member means for feeding the material between them, means for mov-

ing them toward and from one another against the material to print thereon, and separate means for taking up a controlled amount of slack in the material at intervals therealong to control the position of the said 70 designs on the material.

8. A machine for printing a series of 75 separate spaced designs on a continuous length of flexible material comprising a platen, and an impression member, means for drawing the material between them, means for moving them toward and from one another against the material to print thereon and separate means for taking up a controlled amount of slack in the material 80 at intervals therealong to control the position of said designs on the material.

9. A machine for printing a series of 85 separate spaced designs on a continuous length of flexible material comprising a platen, and an impression member, means for feeding the material between them, means for moving them toward and from one another against the material to print thereon, and separate means for taking up 90 a controlled amount of slack in the material at intervals therealong to control the linear distance between successive designs on the material.

10. A machine for printing a series of 95 separate spaced designs on a continuous length of flexible material comprising a platen, and an impression member, means for drawing the material between them, means for moving them toward and from 100 one another against the material to print thereon, and separate means for taking up a controlled amount of slack in the material at intervals therealong to control the linear distance between successive designs on the 105 material.

11. A machine for printing a series of 110 separate spaced designs on a continuous length of flexible material comprising a rotary platen, a printing member, means for 115 drawing material about the platen and means for moving the platen and printing member toward and from one another against the material to print thereon and separate means for taking up a controlled amount of slack in the material at intervals therealong to control the linear distance between successive designs.

12. A machine for printing a series of 120 separate spaced designs on a continuous 125 length of flexible material comprising a rotary platen, a printing member, means for drawing material about the platen and means for moving the platen and printing member toward and from one another 130 against the material to print thereon and separate means for taking up a controlled amount of slack in the material at intervals therealong to control the position of said designs on the material.

13. A machine for printing a series of separate spaced designs on a continuous length of flexible material comprising a rotary platen, a printing member, means for drawing material about the platen and means for moving the platen and printing member toward and from one another against the material to print thereon and a plurality of separate means for taking up a controlled amount of slack in the material at intervals therealong, said slack take up means being arranged to draw the material as it passes around the platen out of line with the periphery thereof to control the linear distance between successive designs.
14. A machine for printing a series of separate spaced designs on a continuous length of flexible material comprising a rotary platen, a printing member means for drawing material about the platen and means for moving the platen and printing member toward and from one another against the material to print thereon and a plurality of separate means for taking up a controlled amount of slack in the material at intervals therealong, said slack take up means being arranged to draw the material as it passes around the platen out of line with the periphery thereof to control the position of said designs on the material.
15. A machine for printing a series of separate spaced designs on a continuous length of flexible material comprising a rotary platen, a printing member, means for drawing material about the platen and means for moving the platen and printing member toward and from one another against the material to print thereon and a plurality of separate means for taking up a controlled amount of slack in the material at intervals therealong, said slack take up means being arranged to draw the material as it passes around the platen out of line with the periphery thereof to control the linear distance between successive designs, said means comprising a slack drawing cross member, means for causing it to project out of line with the periphery of the platen and means associated with the platen for holding all of the material except that part of it immediately adjacent the slack drawing means upon the periphery of the platen.
16. A machine for printing a series of separate spaced designs on a continuous length of flexible material comprising a rotary platen, a printing member, means for drawing material about the platen and means for moving the platen and printing member toward and from one another against the material to print thereon and a plurality of separate means for taking up a controlled amount of slack in the material at intervals therealong, said slack take up means being arranged to draw the material as it passes around the platen out of line
- with the periphery thereof to control the position of said designs on the material, said means comprising a slack drawing cross member, means for causing it to project out of line with the periphery of the platen and means associated with the platen for holding all of the material except that part of it immediately adjacent the slack drawing means upon the periphery of the platen.
17. A printing machine comprising a platen and a printing member, means for feeding a continuous strip of flexible material between them, means for moving them toward and from one another to print thereon, and means operative as the material enters the machine before the printing action has taken place for taking up a controlled amount of slack therein and for holding the slack during the printing operation and until the section of material from which the slack is taken has passed out of the machine.
18. A printing machine comprising a platen and a printing member, means for feeding a continuous strip of flexible material between them, means for moving them toward and from one another to print thereon, and means operative as the material enters the machine before the printing action has taken place for taking up a controlled amount of slack therein and for holding the slack during the printing operation and until the section of material from which the slack is taken has passed out of the machine, there being a plurality of printing members, the slack taking and holding means being arranged to carry the material through the machine in a series of sections arranged for printing with the slack material arranged between the printed sections.
19. A printing press comprising a rotary platen, a printing roller in opposition thereto, a belt traveling over the platen, means for feeding a continuous strip of blank material around the platen between it and the belt and adjustable slack taking members associated with the platen and the belt and independent of the feeding means for taking up a controlled amount of slack in the material to control the distance between successive impressions on the strip.
20. A printing press comprising a rotary platen, a printing roller in opposition thereto, a belt traveling over the platen, means for feeding a continuous strip of blank material around the platen between it and the belt and adjustable slack taking members associated with the platen and the belt and independent of the feeding means for taking up a controlled amount of slack in the material to control the distance between successive impressions on the strip, said means being adapted to take the slack before any printing commences and to hold it until the entire printing action is completed.
21. A printing press comprising a rotary

- 20
- 21 platen, a printing roller in opposition thereto, a belt traveling over the platen, means for feeding a continuous strip of blank material around the platen between it and the belt and adjustable slack taking members associated with the platen and the belt and independent of the feeding means for taking up a controlled amount of slack in the material to control the distance between successive impressions on the strip, the slack take up means being arranged to travel through the printing press at the same rate of speed as the traveling strip of material.
22. A printing press comprising a rotary platen, a printing roller in opposition thereto, a belt traveling over the platen, means for feeding a continuous strip of blank material around the platen between it and the belt and adjustable slack taking members associated with the platen and the belt and independent of the feeding means for taking up a controlled amount of slack in the material to control the distance between successive impressions on the strip, the slack take up means being arranged to travel through the printing press at the same rate of speed as the traveling strip of material.
23. A printing press comprising a rotary platen, a printing roller in opposition thereto, a belt traveling over the platen, means for feeding a continuous strip of blank material around the platen between it and the belt and adjustable slack taking members associated with the platen and the belt and independent of the feeding means for taking up a controlled amount of slack in the material to control the distance between successive impressions on the strip, the slack taking members comprising each a part adapted to draw the material locally away from the face of the platen and means located immediately on either side of such part for holding the balance of the material against the platen face.
24. A printing press comprising a rotary platen, a printing roller in opposition thereto, a belt traveling over the platen, means for feeding a continuous strip of blank material around the platen between it and the belt and adjustable slack taking members associated with the platen and the belt and independent of the feeding means for taking up a controlled amount of slack in the material to control the distance between successive impressions on the strip, the slack taking members comprising each a cross bar adapted to be adjustably projected from the face of the platen, holding bars on the belt spaced one immediately on either side of the cross bar adapted to hold the material against the platen face so as to permit the cross bar to draw it out therefrom.
25. A printing press comprising a rotary platen, a printing roller in opposition thereto, a belt traveling over the platen, means for feeding a continuous strip of blank material around the platen between it and the belt and adjustable slack taking members associated with the platen and the belt and independent of the feeding means for taking up a controlled amount of slack in the material to control the distance between successive impressions on the strip, the slack take up means being arranged to travel through the printing press at the same rate of speed as the traveling strip of material.
26. A printing press comprising a rotary platen, a printing roller in opposition thereto, a belt traveling over the platen, means for feeding a continuous strip of blank material around the platen between it and the belt and adjustable slack taking members associated with the platen and the belt and independent of the feeding means for taking up a controlled amount of slack in the material to control the distance between successive impressions on the strip, said means being adapted to take the slack before any printing commences and to hold it until the entire printing action is completed, the slack take up means being arranged to travel through the printing press at the same rate of speed as the traveling strip of material the slack taking members comprising each a part adapted to draw the material locally away from the face of the platen and means located immediately on either side of such part for holding the balance of the material against the platen face.
27. A printing press comprising a rotary platen, a printing roller in opposition thereto, a belt traveling over the platen, means for feeding a continuous strip of blank material around the platen between it and the belt and adjustable slack taking members associated with the platen and the belt and independent of the feeding means for taking up a controlled amount of slack in the material to control the distance between successive impressions on the strip, the slack taking members comprising each a cross bar adapted to be adjustably projected from the face of the platen, holding bars on the belt spaced one immediately on either side of the cross bar adapted to hold the material against the platen face so as to permit the cross bar to draw it out therefrom.
28. A printing press comprising a rotary

platen, a printing roller in opposition thereto, a belt traveling over the platen, means for feeding a continuous strip of blank material around the platen between it and the belt and adjustable slack taking members associated with the platen and the belt and independent of the feeding means for taking up a controlled amount of slack in the material to control the distance between successive 10 impressions on the strip, said means being adapted to take the slack before any printing commences and to hold it until the entire printing action is completed, the slack taking members comprising each a cross bar adapted to be adjustably projected from the face of the platen, holding bars on the belt spaced one immediately on either side of the cross bar adapted to hold the material against the platen face so as to permit the 15 cross bar to draw it out therefrom.

29. A printing press comprising a rotary platen, a printing roller in opposition thereto, a belt traveling over the platen, means for feeding a continuous strip of blank material around the platen between it and the belt and adjustable slack taking members associated with the platen and the belt and independent of the feeding means for taking up a controlled amount of slack in the material to control the distance between successive 25 impressions on the strip, the slack take up means being arranged to travel through the printing press at the same rate of speed as the traveling strip of material, the slack taking members comprising each a cross bar adapted to be adjustably projected from the face of the platen, holding bars on the belt spaced one immediately on either side of the cross bar adapted to hold the material against the platen face so as to 30 permit the cross bar to draw it out therefrom.

30. A printing press comprising a rotary platen, a printing roller in opposition thereto, a belt traveling over the platen, means for feeding a continuous strip of blank material around the platen between it and the belt and adjustable slack taking members associated with the platen and the belt and independent of the feeding means for taking up a controlled amount of slack in the material to control the distance between successive 45 impressions on the strip, said means being adapted to take the slack before any printing commences and to hold it until the entire printing action is completed, the slack take up means being arranged to travel through the printing press at the same rate of speed as the traveling strip of material, the slack taking members comprising each a cross bar adapted to be adjustably projected from the face of the platen, holding bars on the belt spaced one immediately on either side of the cross bar adapted to hold 50 the material against the platen face so as to permit the cross bar to draw it out therefrom.

permit the cross bar to draw it out therefrom.

31. A printing press comprising a rotary platen, a printing roller in opposition thereto, a belt traveling over the platen, means for feeding a continuous strip of blank material around the platen between it and the belt and adjustable slack taking members associated with the platen and the belt and independent of the feeding means for taking up a controlled amount of slack in the material to control the distance between successive 60 impressions on the strip, the slack taking members comprising each a part adapted to draw the material locally away from the face of the platen and means located immediately on either side of such part for holding the balance of the material against the platen face, and means for adjusting the slack drawing mechanism comprising a cam member on the platen and means for manipulating it to adjust the amount of material which is drawn away 65 from the face of the platen.

32. A printing press comprising a rotary platen, a printing roller in opposition thereto, a belt traveling over the platen, means for feeding a continuous strip of blank material around the platen between it and the belt and adjustable slack taking members associated with the platen and the belt and independent of the feeding means for taking up a controlled amount of slack in the material to control the distance between successive 70 impressions on the strip, said means being adapted to take the slack before any printing commences and to hold it until the entire printing action is completed, the slack taking members comprising each a part adapted to draw the material locally away from the face of the platen and means located immediately on either side of such part for holding the balance of the material against the platen face, and means for adjusting the slack drawing mechanism comprising a cam member on the platen and means for manipulating it to adjust the amount of material which is drawn away 75 from the face of the platen.

33. A printing press comprising a rotary platen, a printing roller in opposition thereto, a belt traveling over the platen, means for feeding a continuous strip of blank material around the platen between it and the belt and adjustable slack taking members associated with the platen and the belt and independent of the feeding means for taking up a controlled amount of slack in the material to control the distance between successive 80 impressions on the strip, the slack take up means being arranged to travel through the printing press at the same rate of speed as the traveling strip of material, the slack taking members comprising each a part adapted to draw the material locally away from the face of the platen.

away from the face of the platen and means located immediately on either side of such part for holding the balance of the material against the platen face, and means for adjusting the slack drawing mechanism comprising a cam member on the platen and means for manipulating it to adjust the amount of material which is drawn away from the face of the platen.

34. A printing press comprising a rotary platen, a printing roller in opposition thereto, a belt traveling over the platen, means for feeding a continuous strip of blank material around the platen between it and the belt and adjustable slack taking members associated with the platen and the belt and independent of the feeding means for taking up a controlled amount of slack in the material to control the distance between successive impressions on the strip, said means being adapted to take the slack before any printing commences and to hold it until the entire printing action is completed, the slack take up means being arranged to travel through the printing press at the same rate of speed as the traveling strip of material the slack taking members comprising each a part adapted to draw the material locally away from the face of the platen and means located immediately on either side of such part for holding the balance of the material against the platen face, and means for adjusting the slack drawing mechanism comprising a cam member on the platen and means for manipulating it to adjust the amount of material which is drawn away from the face of the platen.

35. A printing press comprising a rotary platen, a printing roller in opposition thereto, a belt traveling over the platen, means for feeding a continuous strip of blank material around the platen between it and the belt and adjustable slack taking members associated with the platen and the belt and independent of the feeding means for taking up a controlled amount of slack in the material to control the distance between successive impressions on the strip, the slack taking members comprising each a cross bar adapted to be adjustably projected from the face of the platen, holding bars on the belt spaced one immediately on either side of the cross bar adapted to hold the material against the platen face so as to permit the cross bar to draw it out therefrom, and means for adjusting the slack drawing mechanism comprising a cam member on the platen and means for manipulating it to adjust the amount of material which is drawn away from the face of the platen.

36. A printing press comprising a rotary platen, a printing roller in opposition thereto, a belt traveling over the platen, means for feeding a continuous strip of blank material around the platen between it and the

belt and adjustable slack taking members associated with the platen and the belt and independent of the feeding means for taking up a controlled amount of slack in the material to control the distance between successive impressions on the strip, said means being adapted to take the slack before any printing commences and to hold it until the entire printing action is completed, the slack taking members comprising each a cross bar adapted to be adjustably projected from the face of the platen, holding bars on the belt spaced one immediately on either side of the cross bar adapted to hold the material against the platen face so as to permit the cross bar to draw it out therefrom, and means for adjusting the slack drawing mechanism comprising a cam member on the platen and means for manipulating it to adjust the amount of material which is drawn away from the face of the platen.

37. A printing press comprising a rotary platen, a printing roller in opposition thereto, a belt traveling over the platen, means for feeding a continuous strip of blank material around the platen between it and the belt and adjustable slack taking members associated with the platen and the belt and independent of the feeding means for taking up a controlled amount of slack in the material to control the distance between successive impressions on the strip, the slack take up means being arranged to travel through the printing press at the same rate of speed as the traveling strip of material, the slack taking members comprising each a cross bar adapted to be adjustably projected from the face of the platen, holding bars on the belt spaced one immediately on either side of the cross bar adapted to hold the material against the platen face so as to permit the cross bar to draw it out therefrom, and means for adjusting the slack drawing mechanism comprising a cam member on the platen and means for manipulating it to adjust the amount of material which is drawn away from the face of the platen.

38. A printing press comprising a rotary platen, a printing roller in opposition thereto, a belt traveling over the platen, means for feeding a continuous strip of blank material around the platen between it and the belt and adjustable slack taking members associated with the platen and the belt and independent of the feeding means for taking up a controlled amount of slack in the material to control the distance between successive impressions on the strip, said means being adapted to take the slack before any printing commences and to hold it until the entire printing action is completed, the slack takes up means being arranged to travel through the printing press at the same rate of speed as the traveling strip of material,

the slack taking members comprising each a cross bar adapted to be adjustably projected from the face of the platen, holding bars on the belt spaced one immediately on either side of the cross bar adapted to hold the material against the platen face so as to permit the cross bar to draw it out therefrom, and means for adjusting the slack drawing mechanism comprising a cam member on the platen and means for manipulating it to adjust the amount of material which is drawn away from the face of the platen.

39. A printing press comprising a rotary platen, a printing roller in opposition thereto, a belt traveling over the platen, means for feeding a continuous strip of blank material around the platen between it and the belt and adjustable slack taking members associated with the platen and the belt and independent of the feeding means for taking up a controlled amount of slack in the material to control the distance between successive impressions on the strip, the slack taking members comprising each a part adapted to draw the material locally away from the face of the platen and means located immediately on either side of such part for holding the balance of the material against the platen face, the printing rollers being arranged to print upon that portion of the platen between successive slack taking members so that the slack is taken up in the material between each section of the printed material.

40. A printing press comprising a rotary platen, a printing roller in opposition thereto, a belt traveling over the platen, means for feeding a continuous strip of blank material around the platen between it and the belt and adjustable slack taking members associated with the platen and the belt and independent of the feeding means for taking up a controlled amount of slack in the material to control the distance between successive impressions on the strip, said means being adapted to take the slack before any printing commences and to hold it until the entire printing action is completed, the slack taking members comprising each a part adapted to draw the material locally away from the face of the platen and means located immediately on either side of such part for holding the balance of the material against the platen face, the printing rollers being arranged to print upon that portion of the platen between successive slack taking members so that the slack is taken up in the material between each section of the printed material.

41. A printing press comprising a rotary platen, a printing roller in opposition thereto, a belt traveling over the platen, a means for feeding a continuous strip of blank material around the platen between it and the belt and adjustable slack taking members asso-

ciated with the platen and the belt and independent of the feeding means for taking up a controlled amount of slack in the material to control the distance between successive impressions on the strip, the slack take up means being arranged to travel through the printing press at the same rate of speed as the traveling strip of material, the slack taking members comprising each a part adapted to draw the material locally away from the face of the platen and means located immediately on either side of such part for holding the balance of the material against the platen face, the printing rollers being arranged to print upon that portion of the platen between successive slack taking members so that the slack is taken up in the material between each section of the printed material.

42. A printing press comprising a rotary platen, a printing roller in opposition thereto, a belt traveling over the platen, means for feeding a continuous strip of blank material around the platen between it and the belt and adjustable slack taking members associated with the platen and the belt and independent of the feeding means for taking up a controlled amount of slack in the material to control the distance between successive impressions on the strip, said means being adapted to take the slack before any printing action is commenced, the slack take up means being arranged to travel through the printing press at the same rate of speed as the traveling strip of material the slack taking members comprising each a part adapted to draw the material locally away from the face of the platen and means located immediately on either side of such part for holding the balance of the material against the platen face, the printing rollers being arranged to print upon that portion of the platen between successive slack taking members so that the slack is taken up in the material between each section of the printed material.

43. A printing press comprising a rotary platen, a printing roller in opposition thereto, a belt traveling over the platen, means for feeding a continuous strip of blank material around the platen between it and the belt and adjustable slack taking members associated with the platen and the belt and independent of the feeding means for taking up a controlled amount of slack in the material to control the distance between successive impressions on the strip, the slack taking members comprising each a cross bar adapted to be adjustably projected from the face of the platen; holding bars on the belt spaced one immediately on either side of the cross bar adapted to hold the material against the platen face so as to permit the cross bar to draw it out therefrom, the printing rollers being arranged to print upon

that portion of the platen between successive slack taking members so that the slack is taken up in the material between each section of printed material.

5. 44. A printing press comprising a rotary platen, a printing roller in opposition thereto, a belt traveling over the platen, means for feeding a continuous strip of blank material around the platen between it and the 10 belt and adjustable slack taking members associated with the platen and the belt and independent of the feeding means for taking up a controlled amount of slack in the material to control the distance between successive 15 impressions on the strip, said means being adapted to take the slack before any printing commences and to hold it until the entire printing action is completed, the slack taking members comprising each a cross bar 20 adapted to be adjustably projected from the face of the platen, holding bars on the belt spaced one immediately on either side of the cross bar adapted to hold the material against the platen face so as to permit the 25 cross bar to draw it out therefrom, the printing rollers being arranged to print upon that portion of the platen between successive slack taking members so that the slack is taken up in the material between each section 30 of the printed material.

45. A printing press comprising a rotary platen, a printing roller in opposition thereto, a belt traveling over the platen, means for feeding a continuous strip of blank material around the platen between it and the 35 belt and adjustable slack taking members associated with the platen and the belt and independent of the feeding means for taking up a controlled amount of slack in the material to control the distance between successive 40 impressions on the strip, the slack take up means being arranged to travel through the printing press at the same rate of speed as the traveling strip of material, the slack

taking members comprising each a cross bar 45 adapted to be adjustably projected from the face of the platen, holding bars on the belt spaced one immediately on either side of the cross bar adapted to hold the material against the platen face so as to permit the 50 cross bar to draw it out therefrom, the printing rollers being arranged to print that portion of the platen between successive slack taking members so that the slack is taken up in the material between each section 55 of the printed material.

46. A printing press comprising a rotary platen, a printing roller in opposition thereto, a belt traveling over the platen, means for feeding a continuous strip of blank material around the platen between it and the belt and adjustable slack taking members 60 associated with the platen and the belt and independent of the feeding means for taking up a controlled amount of slack in the material to control the distance between successive 65 impressions on the strip, said means being adapted to take the slack before any printing commences and to hold it until the entire printing action is completed, the slack 70 take up means being arranged to travel through the printing press at the same rate of speed as the traveling strip of material the slack taking members comprising each a cross bar adapted to be adjustably projected 75 from the face of the platen, holding bars on the belt spaced one immediately on either side of the cross bar adapted to hold the material against the platen face so as to permit the cross bar to draw it out therefrom, the 80 printing rollers being arranged to print upon that portion of the platen between successive slack taking members so that the slack is taken up in the material between each section 85 of the printed material.

In testimony whereof, I affix my signature this 12th day of March 1920.

ADELMER M. BATHE.
